GLOVE

George H. Wheadon, Johnstown, N. Y.

Application July 28, 1939, Serial No. 287,023

4 Claims. (Cl. 2—159)

My invention more particularly relates to a glove so formed that the fingers and the thumb and particularly the ends thereof conform better to the fingers and thumb and provide a better fit than gloves which have heretofore been made.

In the usual glove the fingers and thumb of the glove are commonly provided with a seam which is positioned over the pad at the tip of the finger or thumb where it engages articles that are grasped and makes it difficult to pick up or otherwise handle such articles, and the tips of the fingers and the thumb are ill-fitting and uncomfortable. The foregoing feature is further objectionable in that the said seam, at least the portion thereof that thus contacts objects, wears out prematurely.

The principal object of my invention is a glove in which the foregoing difficulty is overcome by providing palm portions both for the fingers and the thumb, and particularly for the latter, which are longer than the back portions of the corresponding members.

Other objects of my invention will appear in the description and the novel features thereof will be particularly pointed out in the claims.

My invention will best be understood by reference to the accompanying drawings in which—

Fig. 1 is a plan view of a glove blank from which the glove embodying my invention is formed;

Fig. 2 is a similar view showing the back of the glove folded over the palm thereof;

Fig. 3 is a fragmentary plan view of a fourchette for a finger;

Fig. 4 is a fragmentary plan view illustrating a portion of the glove and the associated thumb;

Fig. 5 is a plan view of an insert for the thumb of the glove illustrated in Fig. 7 and having a quirk-shaped member that is fitted into a slit in the palm of the glove;

Fig. 6 is an insert on the opposite side of the thumb of the glove illustrated in Fig. 7;

Fig. 7 is a fragmentary plan view of the palm side of a glove embodying my invention;

Fig. 8 is a plan view of a modified form of a blank for an old English thumb which embodies my invention;

Fig. 9 is a plan view of a portion of the palm of a glove to which is attached a modified form of an old English thumb embodying my invention;

Fig. 10 is a plan view of a fragmentary portion of the palm of a glove, the back of the thumb being formed from the blank illustrated in Fig. 8;

Fig. 11 is a plan view of a further modified form of a thumb blank embodying my invention;

Fig. 12 is a plan view of a fragmentary portion of the palm of a glove to which is attached a thumb embodying the blank shown in Fig. 11, and illustrating the end of the palm portion of the thumb turned rearwardly, and

Fig. 13 is a plan view of the glove illustrated in Fig. 12 with the thumb turned inwardly and the tip of the back of the thumb unstitched to the palm thereof.

Like reference characters indicate like parts throughout the drawings.

Referring first to Figs. 1 and 2, it will be noted that the back portions of each of the fingers 10, 101, 102 and 103 are somewhat shorter than the associated palm portions 10a, 101a, 102a and 103a in their unstitched conditions. While not limited to such dimensions, the back portions of the two middle fingers of an ordinary man's glove may be about $\frac{1}{4}$ of an inch shorter than the associated palm portions while the back portions of the first and little fingers may be about $\frac{1}{2}$ of an inch shorter than the associated palm portions.

It will be seen, therefore, that when the back portion 11 of the glove is folded over the palm portion 12 thereof, as illustrated in Fig. 2, that the palm portions 10a, 101a, 102a and 103a of the fingers extend outwardly beyond the corresponding back portions 10, 101, 102 and 103 of the fingers. Prior to the folding operation, a gouge 13 is formed in the blank along the parallel lines 14 of the form shown in Fig. 1 leaving a portion 15 which is integral with the palm 12 of the glove and which forms the palm of the thumb, a slit 16 being provided between the portion 15 and the palm of the glove. The thumb, in the embodiment illustrated in Figs. 1 to 4, may be a long thumb type of glove, both the palm and the back portion of the thumb extending to the edge of the glove cuff. The back portion of the thumb is indicated in Fig. 7 at 17.

An insert indicated at 18 is provided with a quirk-shaped member 19 which is received within a slit 16 and the edges of which are sewed to the palm of the glove and to the palm and back portions of the thumb as indicated in Fig. 7. The opposite side of the thumb is closed by an insert 20 the edges of one end of which are preferably substantially parallel along a portion thereof as at 21 and the free end of which is curved as at 22 to the substantially straight edge 23. The portion 18a of the insert 18 extends along the thumb between the palm and back

50 portions of the two middle fingers of an ordinary man's glove may be about $\frac{1}{4}$ of an inch shorter than the associated palm portions while the back portions of the first and little fingers may be about $\frac{1}{2}$ of an inch shorter than the associated palm portions.

It will be seen, therefore, that when the back portion 11 of the glove is folded over the palm portion 12 thereof, as illustrated in Fig. 2, that the palm portions 10a, 101a, 102a and 103a of the fingers extend outwardly beyond the corresponding back portions 10, 101, 102 and 103 of the fingers. Prior to the folding operation, a gouge 13 is formed in the blank along the parallel lines 14 of the form shown in Fig. 1 leaving a portion 15 which is integral with the palm 12 of the glove and which forms the palm of the thumb, a slit 16 being provided between the portion 15 and the palm of the glove. The thumb, in the embodiment illustrated in Figs. 1 to 4, may be a long thumb type of glove, both the palm and the back portion of the thumb extending to the edge of the glove cuff. The back portion of the thumb is indicated in Fig. 7 at 17.

An insert indicated at 18 is provided with a quirk-shaped member 19 which is received within a slit 16 and the edges of which are sewed to the palm of the glove and to the palm and back portions of the thumb as indicated in Fig. 7. The opposite side of the thumb is closed by an insert 20 the edges of one end of which are preferably substantially parallel along a portion thereof as at 21 and the free end of which is curved as at 22 to the substantially straight edge 23. The portion 18a of the insert 18 extends along the thumb between the palm and back

55 portions of the two middle fingers of an ordinary man's glove may be about $\frac{1}{4}$ of an inch shorter than the associated palm portions while the back portions of the first and little fingers may be about $\frac{1}{2}$ of an inch shorter than the associated palm portions.

It will be seen, therefore, that when the back portion 11 of the glove is folded over the palm portion 12 thereof, as illustrated in Fig. 2, that the palm portions 10a, 101a, 102a and 103a of the fingers extend outwardly beyond the corresponding back portions 10, 101, 102 and 103 of the fingers. Prior to the folding operation, a gouge 13 is formed in the blank along the parallel lines 14 of the form shown in Fig. 1 leaving a portion 15 which is integral with the palm 12 of the glove and which forms the palm of the thumb, a slit 16 being provided between the portion 15 and the palm of the glove. The thumb, in the embodiment illustrated in Figs. 1 to 4, may be a long thumb type of glove, both the palm and the back portion of the thumb extending to the edge of the glove cuff. The back portion of the thumb is indicated in Fig. 7 at 17.

An insert indicated at 18 is provided with a quirk-shaped member 19 which is received within a slit 16 and the edges of which are sewed to the palm of the glove and to the palm and back portions of the thumb as indicated in Fig. 7. The opposite side of the thumb is closed by an insert 20 the edges of one end of which are preferably substantially parallel along a portion thereof as at 21 and the free end of which is curved as at 22 to the substantially straight edge 23. The portion 18a of the insert 18 extends along the thumb between the palm and back

55 portions of the two middle fingers of an ordinary man's glove may be about $\frac{1}{4}$ of an inch shorter than the associated palm portions while the back portions of the first and little fingers may be about $\frac{1}{2}$ of an inch shorter than the associated palm portions.

portions at one side while the insert 20 extends along the opposite side of the thumb, the insert preferably being provided with an angular projection 24 which fits into the recess formed between the palm portion of the thumb and the back portion of the glove. The inserts 18 and 20 illustrated in Figs. 5 and 6 are fully described in my application Ser. No. 264,510 which was filed in the Patent Office March 28, 1939, to which reference may be made for a fuller description thereof.

Fig. 3 illustrates a fourchette for a glove finger which is substantially straight along one edge as at 25 and which is sewed to an edge of the back portion of a glove finger, the opposite edge of the fourchette being parallel with the opposite edge along the main portion thereof and curved at its end as at 26 around the tip of the finger to the point 27 which is disposed at approximately the position of the nail of the finger on which the glove is placed.

In Fig. 4 is illustrated the back portion of the thumb lying against the palm portion thereof, the palm portion extending somewhat beyond the back portion as indicated.

Fig. 5 is a plan view of an insert including a quirk-shaped member;

Fig. 6 is a plan view of a second insert;

Fig. 7 is a plan view of a glove including a thumb embodying my invention;

In Figs. 8 to 13 inclusive is illustrated a modified form of an old English thumb, the palm portion 15 of which may be essentially the same as that illustrated in Figs. 1, 7, 10 and 12. The blank for the back portion of the thumb is indicated at 28 and is provided with a portion 29 which is wider than the palm portion of the thumb illustrated in Figs. 1, 7, 10 and 12 and extends over the thumb of the hand and is sewed at its edges to the edges of the palm portion of the thumb, and is also provided with a quirk-shaped member 19 which is received in and sewed along its edges to the palms of the hand and of the thumb as in the case of the long thumb. The palm portion 15 of the thumb extends beyond the tip of the back portion so that the end thereof curves around to the free end of the back of the thumb as indicated in Figs. 10 and 12.

The blank illustrated in Fig. 11 is similar to that illustrated in Fig. 8 but is provided at its free end with an intermediate member 30 which overlies the thumb nail and with two angular members 31 which are sewed at their edges to the intermediate member 30 to form seams 32 as indicated in Figs. 12 and 13, thereby further improving the fit of the tip of the thumb.

By making the palm portions of the fingers and of the thumb longer than the back portions thereof, the tips of the palm portions of the fingers and of the thumb are caused to curve at their ends outwardly towards the back portion of the fingers and of the thumb in such a way that the seams at the ends of the fingers and the thumb are positioned adjacent the ends of the finger nails and of the thumb nail, respectively, thereby avoiding the usual arrangement in which the fingers and thumb nails of the hand engage the palm portions of the fingers and thumb of the glove thereby avoiding the usual discomfort and wear which is occasioned by the thumb nail and engaging the palm portions of the fingers and thumb of the glove. In the usual form of glove, the wear comes on the seam in the finger and in the thumb while in accordance with my invention the wear comes on the leather.

Fourchettes are thus interposed between the palm portion and the back portion of said thumb, said fourchettes each being substantially straight along one edge and tapered near the end along the other edge, said palm portion, back portion and fourchettes being seamed at their edges and terminating at the end of the portion over the thumb nail.

The result of the improvements embodying my invention is that the front of the fingers and thumbs of the gloves conform to the natural shape and slant of the fingers and thumbs of the wearer and provides a better feeling and a better fitting glove. The seams at the tip come near the back of the tip of the fingers or the thumb of the wearer instead of near the middle of the tip. The seams are out of the way and do not interfere when the hand is used and wear does not come on the seams.

While I have illustrated my invention in a man's glove, it will be understood that it is equally applicable to ladies' gloves.

While I have described my invention in its preferred embodiment, it is to be understood that the words which I have used are words of description and not of limitation. Hence, changes within the purview of the appended claims may be made without departing from the true scope and spirit of my invention in its broader aspects.

30. What I claim is:

1. In a glove, a palm portion and a back portion, a two piece thumb comprising a palm portion and a back portion, the palm portion of said thumb extending forwardly further than said back portion thereof in their unstitched condition, the palm portion of said thumb being turned rearwardly at its end and stitched to the end of said back portion of said thumb, the palm portion of said glove being provided with a slit adjacent said thumb, a first insert disposed between said palm portion and said back portion of said thumb and seamed to the edges thereof and also provided with a quirk shaped member attached at its edges to the edges of the material defining said slit, and also provided with a second insert attached to the opposite side of said thumb from said first insert and provided with a laterally extending projection located adjacent to the crotch formed between the palm of said thumb and the palm of said glove, both of said inserts serving as fourchettes for the upper portion of the thumb.

2. In a glove, a thumb comprising a palm portion and a back portion, said palm portion extending forwardly further than said back portion in their unstitched condition, the palm portion of said thumb being turned rearwardly at its end and stitched to the end of the back portion thereof, fourchettes interposed between the palm portion and the back portion of said thumb, said fourchettes each being substantially straight along one edge and tapered near the end along the other edge, said palm portion, back portion and fourchettes being seamed at their edges terminating at the end of the portion over the thumb nail.

3. In a glove comprising a palm portion and a back portion, a two piece thumb comprising a palm portion and a back portion, the palm portion of said thumb being integral with the palm portion of said glove and narrower and longer than the back portion of said thumb thereby extending forwardly further than the back portion of said thumb in its unstitched condition and

bringing the seam at the tip of the thumb along the tip of the nail thereby improving the fit and wearing qualities of the thumb at the tip thereof.

4. In a glove, a finger comprising a palm portion and a back portion; said palm portion extending forwardly further than the back portion in their unstitched condition; fourchettes positioned between said palm and back portion, and seams securing said fourchettes and said palm and back portions together; the seams securing 10

said fourchettes to said back portion being substantially straight, the seams securing said fourchettes to said palm portion being curved towards said back portion near the tips of the fingers, and a seam at the tip of the finger being positioned substantially at the tip of the finger nail when said glove is worn; whereby fitting and wearing qualities of the glove at the finger end are improved.

GEORGE H. WHEADON.
